UNITED STATES PATENT OFFICE.

JOHN R. BARKER, OF CHICAGO, ILLINOIS.

AIR-HEATING FURNACE.

SPECIFICATION forming part of Letters Patent No. 402,795, dated May 7, 1889.

Application filed November 27, 1888. Serial No. 292,039. (No model.)

To all whom it may concern:

Be it known that I, JOHN R. BARKER, a citizen of the United States of America, residing at Chicago, in the county of Cook and State 5 of Illinois, have invented certain new and useful Improvements in Air-Heating Furnaces, of which the following is a specification, reference being had therein to the accompanying drawings.

10 This invention relates to improvements on the furnace for which Letters Patent of the United States were granted to me on May 28, 1872, being No. 127,140, and on September 22, 1885, being No. 326,541; and it has for its object to provide certain improvements thereto; and my invention consists of the novel devices and combinations of devices hereinafter described and specifically claimed.

15 In the accompanying drawings, Figure 1 represents a longitudinal vertical section, and Fig. 2 a transverse vertical section, through the center of the furnace. Fig. 3 is a sectional plan on line 3 3 in Fig. 1, and Fig. 4 is a sectional plan on line 4 4 in Fig. 1. Fig. 5 20 represents an elevation of the furnace, the outer shells or casing being removed, and Fig. 6 shows a plan of the water-receptacle detached.

25 Corresponding letters of reference in the several figures of the drawings designate like parts.

A denotes the base of the furnace, also providing the bottom for the ash-pit B, having door a. The ash-pit casting B supports the 30 fire-pot C, and below this fire-pot the grate D, having shaker-arm b, is pivoted upon a dump-frame, c, having trunnions to its rear that rest in U-shaped brackets d, forming part of the ash-pit casting, while its forwardly 35 projecting arm is supported by a swinging bolt, e, that can be swung to clear such arm and allow the grate to be lowered for removing the clinkers in the ordinary well-known manner. Upon the upper grooved edge of 40 the fire-pot C is placed a ring-chamber, R, made in halves bolted together and provided with an air-inlet opening, f, and with a series of internal vents, g, that will admit atmospheric air to enter in small jets and mix with the 45 gases generated from the fuel to make them combustible, and thereby utilize the same and

economize fuel. Upon this ring-chamber R is fitted the somewhat conical combustion-chamber composed of sections E, F, and G, the sections E and F also providing the fuel-feed 55 channel h with fuel-door i, and the section F having cast a series of elbow-shaped gas-outlet extensions, j, communicating with nozzles K, forming part of section F. The uppermost section, G, is cylindrical, and is closed on 60 top by a concaved circular plate, l.

An upper ring-shaped chamber, H, has a series of downwardly-projecting nozzles, m, connecting with the nozzles k of combustion-chamber section E for supporting chamber 65 H and for providing a series of communicating flues between the combustion-chamber and ring-shaped chamber H, and between this chamber H and another ring-shaped chamber, I, placed to surround the fire-pot C, is 70 provided communication through a series of pipes, J, one for each two flues, K m. The ring I has a thimble, n, projected through the casing and provided with a nozzle for connecting smoke-pipe K, and also provided at 75 its end with a door, o, arranged to be adjustably opened for admitting air to check the draft of the furnace, if desirable. This smoke-pipe K is also connected with a thimble, p, forming part of ring-chamber H to afford 80 communication therewith and to let the gases escape direct from such upper ring-chamber, H, whenever it is desirable to produce a strong draft, and this thimble p is provided with a damper, q, which with closing will cause the 85 gases to circulate through the lower ring-chamber, I. The upper ring-chamber, H, is also pierced by a series of vertical flues, r, for air to be heated to rise through the same.

Upon standard lugs s forming part of ribs 90 t of base A is placed the horseshoe-shaped water-receptacle M, having a pipe tapped into one side, which pipe extends through the casing, where a spout-casting, Q, is connected thereto provided with a cover for feeding water into such receptacle, which water will evaporate into the air passing through the furnace to be heated therein for impregnating such air with the required moisture to make it healthful.

100 This furnace is incased with galvanized sheet-metal shell N, made in cylindrical sec-

tions connected by cast-metal rings *v* and closed on top by a crown-sheet, *w*, which is to be provided with openings for the hot-air-conducting pipe, to be connected therewith in the usual manner, and inside of shell *N* another cylindrical shell, *P*, is supported on hooks *x*, secured to one of the rings *v*, for retaining the heat in the furnace and for preventing the outer shell from becoming heated.

10 What I claim is—

1. In an air-heating furnace, the combination, with fire-pot *C* and combustion-chamber composed of the parts *E* and *F*, the former being provided with elbow-pipes *j* and nozzles *k*, extending upward, of the ring-chamber placed on a higher level than the combustion-chamber and having downwardly-extending nozzles *m*, connecting with nozzles *k* to form communicating flues, and the ring-chamber *I*, surrounding the fire-pot, and the pipes *J*, connecting the chambers *H* and *I*, as set forth.
2. In an air-heating furnace, the combination, with fire-pot *C* and combustion-chamber

E F, the former being provided with elbow-pipes *j* and nozzles *k*, of ring-chamber *H*, located above the combustion-chambers and pierced with air-circulating tubes *r*, and provided with nozzles *m*, to connect with nozzles *k*, and of ring-chamber *I*, surrounding the fire-pot and communicating with ring-chamber *H* through pipes *J*, all substantially as set forth.

3. The combination, with an ash-pit, a fire-box, combustion-chamber, and ring-chambers surrounding said fire-box and combustion-chamber, of a horseshoe-shaped water-receptacle placed below the ring-chambers and partially surrounding the ash-pit, and a spout-casting, *Q*, on the outside of the furnace-shell, and a pipe connecting the trough *M* and said casting, as set forth.

In testimony whereof I affix my signature in presence of two witnesses.

JOHN R. BARKER.

Witnesses:

WILLIAM H. LOTZ,
OTTO LUBKERT.
